UNITED STATES PATENT OFFICE

2,072,732

SPARK PLUG

Philip K. Devers, Lynn, Mass., assignor to General Electric Company, a corporation of New York

Application August 28, 1935, Serial No. 38,183

5 Claims. (Cl. 123—169)

The present invention relates to the construction of spark plugs intended for use in internal combustion engines. In particular, my invention relates to spark plugs containing insulators of fused silica although it is not restricted in its use to silica insulators.

My invention in some aspects constitutes features of improvement over the spark plugs shown and described in prior U. S. Patent No. 1,869,133 issued on July 26, 1932 to Devers and Hooper.

Although silica possesses superior insulating properties which especially adapt it for use at high temperatures, silica insulators in spark plugs have been found in some cases subject to breakage when under pressure and in operation at temperatures varying over a wide range. I have found that one cause for such breakage is the difference in rate of expansion of the silica and the metal conductor of the plug with its surrounding cement which are imbedded in the duct or passage extending longitudinally through the insulator.

It is the object of my invention to improve the resistance to breakage or cracking of insulators in spark plugs and to improve their electrical characteristics.

In accordance with one feature of my invention the conductor which extends longitudinally through the insulator of a spark plug is sealed to the insulator only at a restricted region or regions, near one, or both ends of the insulator, the rest of the wire extending through the bore of the insulator loosely or, in other words, in spaced relation to the wall of the passage.

In accordance with another feature of my invention the elasticity of the insulator is improved by a median enlargement which is provided with a groove.

These and other features of my invention will be described in connection with the accompanying drawing in which Fig. 1 is a vertical section of a spark plug embodying my invention; and Fig. 2 is a vertical section of a spark plug (in part broken away) provided with a modified housing.

As shown in the drawing, the spark plug includes a metal case 1, which is screw-threaded externally at its lower end for engagement with a screw-threaded orifice in an internal combustion engine. The metal casing may consist of two members *a* and *b*, which are threaded to engage with one another and with the elongated insulator 2, cushioning gaskets or washers 3, 4 being provided between the metal casing members *a* and *b* and a bulbous central enlargement of the insulator. The gaskets 3, 4 may consist of a soft metal such as pure copper or of a soft alloy, such as the alloy described in U. S. Patent No. 1,177,407 to Gilson, or of a textile material bonded with an artificial resin (Texto-

lite) and containing a lubricant, such as graphite. The bulbous enlargement of the insulator 2 merges with smooth, non-angular transition surface with a firing tip 5 and externally projecting shaft 6. A duct or passage 7 extends longitudinally through the insulator for the reception of a conductor 8. A sparking terminal 9 projects from the tip of the insulator into sparking relation with a sparking terminal 10 projecting from the casing 1. The conductor 8 is of somewhat lesser diameter than the diameter of the passage 7. The clearance between the conductor 8 and the wall of the passage 7 is about three to six mils.

At the upper extremity of the shaft 6, a flattened section of the conductor 8, as indicated at 11, is fusion-sealed into the silica, a similar seal 12 being shown at the bottom. Seals of this type are well understood, being described in U. S. Patent No. 1,271,245 to Von Recklinghausen, patented July 2, 1918. It is desirable to have the main part of the conductor 8 consist of metal, for example, metal particularly adapted to resist high temperatures and erosion. With this object in view the conductors 9 and 10 may be plated with chromium. The sealed-in portion 11, 12 of the conductor 8 may consist of a metal such as molybdenum, which is well adapted for sealing into silica. The ribbon-shaped or flattened parts or members 11 and 12 which are sealed into the silica may have a length of about 7 mm., a width of about 3 mm. and a thickness of about 0.2 to 0.3 mil. While in some cases as shown both extremities of the conductor 8 as indicated, 11 and 12, are fusion-sealed into the silica leaving the main intermediate portion of the conductor 8 spaced from the wall of the passage so that expansion of the conductor due to heat will not cause cracking of the silica insulator. The lower seal 12 in some cases may be omitted, the space around the wire 8 being open at the firing tip.

In order to further improve the yieldability of the insulator under pressure a groove or depression 13 is provided on the exterior of the spherical enlargement of the insulator 2. This depression may be produced by rolling during the fabrication of the insulator which may be carried out by process and apparatus described in U. S. Patent No. 1,814,205 patented June 13, 1933. The depression 13 may have a depth of about $3/64''$ to $5/64''$. If the groove is too shallow it may promote breakage of the insulator across the shaft 6 at its junction with the enlargement. If it is too deep the cracks will extend from the bearing between the gasket and the insulator to the bottom of the depression.

Surrounding the shaft 6 is a hood 15 which may consist of a suitable insulating material and is screwed into the shell member *a*. It is provided

with vent holes 16 as illustrated. A light spring 17 is provided between the external terminal 18 and the top of the shaft 6 of the insulator.

If the hood is to function as a radio shield, as well as a mechanical shield, it may be constructed in part of metal, for example, as shown in Fig. 2. As there illustrated, a short metal tube 19 is provided which is conveniently threaded to the spark plug shell 1. Mounted upon this metal tube 19 is an insulating tube 20 into which projects a radio-shielded conductor 21 which leads to the electrical ignition system. This conductor 21 makes electrical connection to the spark plug terminal 22 through a connecting tube 23. The metal sheath 24, which surrounds the insulation 25 of the conductor 21, is grounded by a wire 26 to the metal member 19 of the spark plug shield.

What I claim as new and desire to secure by Letters Patent of the United States is:

1. A spark plug comprising an elongated insulator of vitreous material, said insulator having a longitudinally extending cavity, a conductor within said cavity, said conductor having a firing tip and having a diameter which is less than the diameter of said cavity whereby a clearance space is left between said conductor and the wall of said cavity, said conductor being sealed by local fusion of said insulator, and a casing surrounding said insulator consisting in part of metal and in part of insulating material, said parts engaging with one another.

2. A spark plug comprising an elongated silica insulator having a longitudinally extending cavity, a conductor within said cavity having a fir-

ing tip projecting therefrom, the diameter of said conductor being less than the diameter of said cavity and having a section of reduced thickness fusion-sealed into said insulator remote from said firing tip.

3. A spark plug comprising a casing, an elongated silica insulator having a median, externally grooved enlargement and a longitudinally extending cavity, means for pressure-sealing the enlargement of said insulator in said casing, a conductor within said cavity, with a clearance space from the wall of said cavity and having a firing tip projecting out of said cavity and being fusion-sealed into said silica insulator so as to leave clearance space adjacent said enlargement of said insulator.

4. A spark plug comprising a casing, an elongated silica insulator mounted therein, said insulator having a longitudinal passage, a conductor having a lesser diameter than said passage and extending therethrough, said conductor having a flat, ribbon-shaped part sealed into said insulator by fusion of the adjacent silica.

5. A spark plug comprising a casing, a silica insulator mounted therein, and having a longitudinal passage and a median enlargement, a conductor of lesser diameter than said passage extending through and projecting beyond said insulator, said conductor having at least one member of ribbon-shaped form which is fusion-sealed into said insulator at a region remote from said enlargement leaving a clearance space about said conductor adjacent said enlargement.
